Primary Examiner — Susan Bennett Hattan*Assistant Examiner* — Rebecca Tsehay(74) *Attorney, Agent, or Firm* — Price Heneveld LLP(57) **CLAIM**

The ornamental design for a dryer, as shown and described.

DESCRIPTION

FIG. 1 is a front perspective view of a dryer according to our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of various features is for the purpose of illustrating unclaimed portions of the washing machine and forms no part of the claimed design.

Dash-dot lines adjacent un-shaded areas represent bounds of the claimed design and form no part thereof.
